GAME TABLE

Isabel G. Eaton Homan, Phoenix, Ariz.

Application August 8, 1950, Serial No. 11,670

Term of patent 3½ years

(Cl. D33—14)

To all whom it may concern:

Be it known that I, Isabel G. Eaton Homan, a citizen of the United States, residing at Phoenix, in the county of Maricopa, State of Arizona, have invented a new, original, and ornamental Design for a Game Table, of which the following is a specification, reference being had to the accompanying drawing, forming a part thereof:

Fig. 1 is a top plan view of a game table, embodying my new design;

Fig. 2 is a side elevation thereof, the legs being partially omitted for convenience in illustration;

Fig. 3 is a perspective view of the game table;

Fig. 4 is a cross-sectional view taken on line 4—4 of Fig. 1; and Fig. 5 is a cross-sectional view taken on line 5—5 of Fig. 1. The essential features of my design are shown in full lines.

I claim:

The ornamental design for a game table, as shown and described.

ISABEL G. EATON HOMAN.
